UNITED STATES PATENT OFFICE.

JOHN HOLMES BARNES, OF GREENCASTLE, INDIANA.

SAFETY ATTACHMENT.

SPECIFICATION forming part of Letters Patent No. 334,926, dated January 26, 1886.

Application filed October 23, 1885. Serial No. 180,771. (No model.)

To all whom it may concern:

Be it known that I, JOHN H. BARNES, of Greencastle, in the county of Putnam and State of Indiana, have invented a new and 5 useful Improvement in Safety Attachments, of which the following is a description.

My invention is an improved safety attachment intended especially for use in watch-pockets; and the invention consists in certain 10 novel constructions, combinations, and arrangements of parts, as will be hereinafter first fully described, and then pointed out in the claims.

In the drawings, Figure 1 is a back view, 15 and Fig. 2 a top plan view, of a pocket provided with my improvements. Fig. 3 is a perspective view of my attachment with dotted motions, and Fig. 4 shows a modification.

The pocket A may manifestly be that of a 20 vest or of a pair of pantaloons. Through the rear side of one end of the pocket it is preferred to form an opening, a, for the rear end of the safety attachment, which bears the detent and projects into position to be manipulated from the inner side of the garment, or 25 the attachment may be secured wholly within the pocket where desired. The attachment consists of a plate, forming the support, a hooked bar, and a detent. The supporting- 30 plate B may have suitable openings to facilitate its stitching to the pocket, or the plate may be secured in other desired manner. It has its forward edge bent, forming an approximately right-angled flange, b, which is formed 35 with openings b' b'' for the passage of the hooked bar. The flange b is extended at C and bent or curved, forming the chain-retaining hook, as will be presently more fully described. A keeper or loop, D, on the support 40 operates in connection with opening b' to receive and guide the hooked bar E. This keeper and the rear end of the bar are preferably made angular to prevent such bar from rotating and preserve it at all times in operative position. A flange or enlargement, e, 45 on the rear end of the bar E, by engagement with the keeper D, limits the forward movement of the hooked bar. The forward end of the bar is passed through opening b', and 50 bent, forming hook E', the extremity of which is movable into and out of opening b''. A notch, e', is formed in the bar near its rear

end in position to be engaged by a detent-pawl, F, pivoted at one end, and having its other end arranged to engage the bar E and 55 secure same in the position shown in Fig. 3. When in this position, forward strain on the hooked bar will only bind the detent more firmly in place. By turning the detent down the hooked bar is released, and may be adjusted to the position indicated in dotted lines, 60 Fig. 3, when the pendent ring of the watch may be engaged by or released from the hooked bar, which may be securely locked by moving it back so the point of the hook will enter the 65 opening b'', and the detent-pawl engages the notch e', as will be seen. When so secured, the watch can only be removed by releasing the detent and adjusting the hooked bar to the dotted position indicated in Fig. 3. If it 70 is not desired to hook the watch, the chain may be passed up within the hook C, so as to prevent the watch being withdrawn. This hook is also useful in that it retains the chain over the supporting-plate, so as to prevent 75 such chain from pulling down the pocket, as will be seen.

Manifestly the form of the detent may be varied. In this connection the hooked bar might be slotted and secured by a screw and 80 thumb-nut, as shown in Fig. 4; but I prefer the pawl-detent for the reasons before stated.

Having thus described my invention, what I claim as new is—

1. In a safety attachment for pockets, the 85 combination of a plate or main portion provided with a chain-supporting hook, and a lock supported by said plate, and provided with a watch-securing device, all constructed and arranged substantially as described, where- 90 by the watch may be secured and the chain passed up over the hook, as set forth.

2. In a safety attachment for watch-pockets, the combination of the plate or support having end flange, b, extended to form the chain- 95 supporting hook C, the locking-bar having a hook at one end, whereby to secure a watch, and a detent arranged to engage said bar, sub- stantially as set forth.

3. As an improved article of manufacture, 100 the safety attachment for watch-pockets herein described, consisting of a supporting-plate, a bar provided with a hook whereby to engage a watch-ring, and supported by and

movable along said plate, and provided with a notch, e' , and the detent F, pivoted at one end to the plate, and made of a length to engage at its free end with notch e' at a point in 5 rear of its pivotal support, whereby strain on the bar E will tighten the detent, substantially as set forth.

4. A safety attachment consisting of a supporting plate, B, having a right-angled flange, 10 b , provided with perforations $b' b^2$ and ex-

tended, forming a hook, C, a keeper, E, secured on said plate B, the hooked bar having a notch, e' , and the detent-pawl, pivoted at one end to the plate B, and having its other end movable into and out of engagement with notch e' , substantially as set forth. 15
